UNITED STATES PATENT OFFICE.

ELIZA WOOD, OF SHAWNEE, OKLAHOMA.

METHOD OF MAKING DRESS-FORMS.

1,202,633.

Specification of Letters Patent. Patented Oct. 24, 1916.

Application filed March 18, 1913. Serial No. 755,208.

To all whom it may concern:

Be it known that I, ELIZA Wood, a citizen of the United States, residing at Shawnee, in the county of Pottawatomie and State 5 of Oklahoma, have invented new and useful Improvements in Methods of Making Dress-Forms, of which the following is a specification.

This invention relates to dress makers' 10 forms and the method of making the same.

One of the principal objects of the invention is to produce a form in the simplest and most inexpensive manner which will be an exact reproduction of the form of 15 the person to which the garment is to be fitted.

Further objects of the invention will appear as the following description is read in connection with the accompanying drawing, which forms a part of this application, 20 and in which:—

Figure 1 is an elevation of the form. Fig. 2 is a detail sectional view therethrough.

25 Referring to the drawing, 1 represents a base of any suitable character which has projecting vertically therefrom a standard 2 provided with the set screw 3. This standard supports the form which consists 30 of a base board 4 and a body constructed of the inner lining 5, the coating and impregnating layer 6 of plaster and the outer covering of paper 7. The body is provided with overhanging flanges 8 and a collar 9. 35 The flanges 8 are provided to insure proper fit of the sleeves and to prevent wrinkling of the garment at this point when fitted over the form.

In carrying out the method of producing 40 the form a lining 5 is taken which is constructed of any suitable material, preferably material which is cheap and yet has the qualities of absorbing or taking up a quantity of semi-liquid plaster Paris or 45 similar material. This lining 5 is fitted to

the person for whom the garment is intended by pinning the same tightly and smoothly over the corset and extending the same down to the lower portion of the hips. After the first fitting the waist thus formed 50 is properly stayed, and the waist again fitted to the person and pinned very tight in the back. It is then removed and stitched up the back and throughout the collar. A rubber bag is then placed in the form and 55 inflated until the waist tightly fits the same, at which time the waist is given a coat of semi-liquid plaster Paris which partially impregnates the fabric, and is then allowed to harden. The form is then stuffed with 60 excelsior, paper or other similar material and the base board 4 tacked or otherwise secured thereto. The entire form is then covered with paper or any other material desired, the paper or other material being 65 preferably pasted to the plaster Paris coat. The form is then ready to have the waist fitted thereover. It will also be noticed that with a form of this character skirts may be fitted upon the same and as the 70 standard is adjustable the device is adapted for use with persons of varying heights.

What is claimed is:—

The process of making a form which consists of first shaping an inner lining to the 75 proper bust configuration, thereafter applying an inflatable backing inside of and against said lining, then inflating the inflatable backing to cause said lining to tightly fit the same, thereafter applying a 80 plastic coating against the outer surface of said lining, then applying a proper outer lining upon said plastic coating, and lastly stuffing the form with a suitable material.

In testimony whereof I affix my signature in presence of two witnesses.

ELIZA WOOD.
